UNITED STATES PATENT OFFICE.

ARTHUR JOHNSON, OF REMSEN, IOWA.

WIRE-STRETCHING DEVICE.

1,277,317.

Specification of Letters Patent. Patented Aug. 27, 1918.

Application filed April 16, 1917. Serial No. 162,468.

To all whom it may concern:

Be it known that I, ARTHUR JOHNSON, a citizen of the United States, and resident of Remsen, in the county of Plymouth and State of Iowa, have invented certain new and useful Improvements in Wire-Stretching Devices, of which the following is a specification.

This invention relates to new and useful improvements in pulling devices, and more particularly to wire stretchers, and the primary object of the invention is to provide a device of this character that is adapted to grip the wire, and also stretch the same to the desired tension, the device being applicable to a fence post, or rigidly secured in the ground.

Another object of the invention is to provide a wire stretcher of this character that is provided with an efficient means of attaching the same to a fence post or similar standard, said means being adjustable, so that the device is applicable to standards of various sizes.

Still another object of the invention is to provide a wire stretching device of this character that is provided with a new and novel means for gripping the wire, after the same is stretched, so that the wire will not be allowed to return to its original position, when the primary pulling means of the device are released.

A further object of the invention is to provide a device of this character which is easily and simply constructed, inexpensive to manufacture, and one which will be very efficient in operation.

With these and numerous other objects in view my invention consists of the novel features of construction, combination and arrangement of parts which will be herein-referred to and more particularly pointed out in the specification and claims.

In the accompanying drawings:

Figure 1 is a side elevation of the device; Fig. 2 is a top plan view of the same applied;

Fig. 3 is a detailed side elevation of the front end of the device;

Fig. 4 is a perspective view of the gripping jaws at this end of the device;

Fig. 5 is an end elevational view, taken from the rear end thereof;

Fig. 6 is a detailed perspective view of the detachable gripping means secured to the bottom of the main frame;

Fig. 7 is a horizontal section of the same, and

Fig. 8 is a detailed perspective of the means employed for releasing the gripping jaws at the front end of the device.

In describing my invention I shall refer to the drawings in which similar reference characters designate corresponding parts throughout the several views.

The numeral 1 designates as an entirety the main frame of this device, which is substantially rectangular in shape, having front and rear end portions 2 and 3, and top and bottom portions 4 and 5 respectively. This frame is formed of any desired material, preferably metal, so as to give the requisite strength and durability to the device. The frame 1 is normally disposed in upright position, and secured to the front portion 2

thereof on opposite sides of the same are gripping jaws 6, while fulcrumed to the rear edge of the rear portion 3 is an operating lever 7, which is also provided with gripping jaws 8 on the opposite sides thereof, normally disposed in horizontal alignment with the gripping jaws 6. The jaws 6 and 8 are provided on opposite sides of the device, so as to accommodate different sizes of wire or cable, that are to be pulled, the jaws at one side, being relatively smaller than the opposite jaws, and the jaws that engage the larger wire are preferably formed

with supplemental gripping means comprising a projected serrated portion, as clearly shown in Fig. 4 of the drawings. For the sake of brevity I will only specifically describe one of these sets of jaws, as the other set is substantially like it in general detail.

The jaws 6 at the front end of the frame 1, are formed of bell crank levers 7 pivoted as shown at 8', and having jaws 9 formed on the outer edges of their horizontally extending portions. These jaw members 9 are adapted for coaction, to securely grip a wire or cable therebetween. The outer ends of the opposite portions of the levers 7 are

connected by coiled springs 10 with the front portion 2 of the frame, so as to normally dispose the coacting jaws 9 into operative engagement, as clearly shown in Fig. 1 of the drawings.

These jaws 6 are provided with releasing means, which include a pair of angular levers 11, mounted in bearings 12 secured to the outer edge of the front portion 2 of the frame 1, one portion of one of the levers 11 extending therefrom as shown at 13 to form a handle to operate this means. The adjacent ends of the levers 11 are connected by a link 14, and each of the levers are connected by links 15 with the ends of the levers 7 adjacent the coiled springs 10. The various parts of this releasing mechanism are normally disposed as shown in Fig. 1 of the drawings, and when it is desired to release the jaws 6, the handle 13 is grasped and swung upwardly, whereupon the levers 11 will be moved, to swing the jaws open through their connection therewith by means of the links 15. This movement will be 25 against the tension of the springs 10, and hence upon releasing the handle, the jaws will return to normal position.

The primary pulling means of this device consist of a lever 7, that is fulcrumed at its lower end to the edge of the rear portion 3 of the frame 1, adjacent the bottom of the same. This lever 7 is formed in two sections, the lower section being designated by the numeral 16, and the upper section by 35 the numeral 17. The section 16 is provided with a projection 18 on its upper end, and the lower end of the section 17 is bifurcated as shown at 18', and adapted to co-operatively engage this projection, so that the two 40 sections will be pivotally connected, and will have a limited swinging movement with respect to each other. The jaws 8 comprise jaws 19 secured to the section 16 of the lever, and co-acting jaws 20 secured to the 45 section 17. When the two sections of the lever 7 are disposed in alinement, the jaws 8 will be co-operatively related, but when the sections of the lever are disposed out of alinement, the said jaws will be spaced from 50 each other, so that a wire may be easily placed between the same, or removed therefrom. To normally hold a wire in position between these jaws, I have provided a supplemental holding means which includes a 55 pair of strips 21, that are slidably mounted on the section 17, on the opposite sides thereof, and are connected at their upper ends by a handle 22, the lower ends of said strips being outwardly flared as shown at 23, and 60 normally disposed adjacent the opposite sides of the jaws 8. These outwardly flared portions will consequently be disposed over the opposite sides of the jaws in no matter what position the same are disposed, so as

to securely hold wires positioned between 65 said jaws into engagement therewith. A coiled spring 24 connects the handle 22, and the outer edge of the section 17 of the lever 7, so as to normally hold these strips in operative position over the jaws. It is obvious 70 that to release this holding means, it is necessary to grasp the handle 22, and lift the same against the tension of the coiled spring 24, whereupon the wires may be easily removed or replaced, and upon releasing the 75 handle, the holding means will return to normal position, as clearly shown in Fig. 5 of the drawings. The upper section 17 is provided with a supplemental handle 25 so as to give additional leverage to the device. 80

To securely connect the upright frame 1 to a fence post, or similar standard, I have provided a laterally projecting arcuately curved arm 26 provided with studs on its inner surface as shown at 27, said arm being secured to one side of the bottom portion 5 of the main frame, said portion or outer side thereof having alining projecting studs 28 thereon, which coact with the studs 27 to securely engage the fence post or 90 standard. Secured to the outer end of the arm 26 is a correspondingly curved lever 29, which has connected therewith one end of a chain, or other flexible element 30, said chain being adapted to extend around the fence 95 post or standard, and to be connected with the bottom portion 5 of the main frame. The free end of the chain 30 is adjustably connected with the portion 5 of the main frame by means of a sliding block 32 having a split spaced portion 33 adapted to receive one of the links of the chain 30 therebetween. This block is slidably adjustable on the portion 5 of the frame, and it is obvious that any of the links of the chain are 100 adapted to be connected therewith. By this means the chain may be tightened around the fence post or standard, and upon swinging the lever 29 into position adjacent the arm 26, the device may be securely clamped 110 to the fence post or standard. The outer end of the arm 26 is provided with a guide portion 33', as clearly shown in Fig. 2 of the drawings.

Secured to the bottom edge of the portion 115 5 of the frame 1 are a pair of arcuate gripping members 34, which have dove-tailed upper ends as shown at 35, adapted to engage dove-tailed slots 36 on projecting blocks 37 integral with the portion 5. These members 34 are to securely fasten the frame 1 in the ground in upright position, when the device is used close to the ground, or as a pulling device for various purposes. Owing to the fact that the members 34 are detachable, they may be removed, when it is desired to use the device only as a wire 125 stretcher.

In operation when it is desired to use this device for stretching wire to the desired tension, the frame is positioned adjacent a fence post or similar standard, with the arm 26 in engagement therewith. When in this position the projecting studs 27 and 28 will bite into the post, and then the lever 29 on the end of the arm 26 is swung out, and the chain swung around the post, and engaged with the block 32 on the portion 5. The lever 29 is then swung back to its original position, and locked by the member 31 whereupon the device will be securely clamped to the post, the frame being disposed upright with respect thereto.

When securely held in this position, the wire is positioned through the jaws 6 at either side of the frame, this being accomplished by grasping the handle 13, thereby swinging said jaws apart, by drawing them against the tension of the coiled springs 10 and after the wire has been placed therebetween the handle 13 is released, and the springs will return said jaws to their normal position. This connection will be sufficient to securely grip the wire, and hold the same against the tension that is exerted by the main body of the wire being held in stretched position on the fence. To tighten the wire to the desired tension, the free end is operatively engaged by the lever 7. This is accomplished by lifting the wire holding means that is normally disposed over the jaws 8, and by swinging the upper section 17 of said lever forwardly, out of alinement with the section 16, whereupon the jaws will be spaced apart, and the wire may be easily placed therebetween. When the wire is in position the holding means is released, and the sections of the lever are once more swung back into alinement. From this position the lever 7 may be swung rearwardly away from the frame 1, in a substantially vertical plane therewith, whereupon the free end of the wire will be pulled in that direction, and through the gripping jaws 6 at the front of said frame. The gripping jaws while holding the wire from forward movement, will not prevent the same being drawn rearwardly through movement of the lever 7. When the lever 7 has reached the limit of its rearward movement, the section 17 thereof is swung forwardly out of alinement with the section 16, whereupon the jaws 8 will be spaced apart, and the lever may be once more returned to its original position. The holding means adjacent said lever will keep the wire positioned between the jaws, and will prevent its slipping therefrom when the lever is being returned. The gripping jaws 6 at the front of the frame will prevent the wire from returning to original position, when the free end is released from the pulling lever, consequently

allowing an additional pull to be placed thereon after the lever has been returned to its original position.

This device is applicable for various other uses beside stretching wire, as the same may be employed with a cable for pulling automobiles from mudholes, or similar purposes. When the device is used for this purpose, one end of the cable is connected with the hook 38 on the front end of the frame 1, and the cable is trained over a pulley secured to the vehicle, and run back through the gripping jaws 6 and 8 on the frame 1. The members 34 on the bottom of the frame are positioned in the ground so as to rigidly secure the frame in upright position, and thereupon when the device is operated as has been hereinbefore described, the free end of the cable may be pulled gradually, so as to exert considerable power on the same to accomplish the desired purpose. The pull in a device of this character is gradual, the same being intermittent due to the movement of the lever 7 backward or forward. The pull is exerted it is obvious only when the lever 7 is moved rearwardly, the return movement of said lever being only to give it a fresh position on the free end of the wire or cable which it is engaging.

From the foregoing description, taken in connection with the accompanying drawings, the advantages of the construction and method of operation will be readily apparent to those skilled in the art to which the invention appertains, and while I have described the principle of operation of the invention together with the device which I now consider to be the best embodiment thereof, I desire to have it understood that the device shown is merely illustrative and that such changes may be made when desired as are within the scope of the claims appended hereto.

Having fully described my invention, what I claim as new, and desire to secure by Letters Patent, is:

1. A wire stretching device of the class described comprising a frame, means carried thereby at one end for engaging the free end of a wire and pulling the same in one direction, a pair of spring tensioned gripping jaws at the other end of said frame adapted for normal continuous engagement with said wire to prevent reverse movement thereof, a pair of angular simultaneously operable levers pivoted to said end of the frame, and links connecting said levers and jaws whereby the jaws are adapted to be open against spring tension upon operation of the levers.

2. A wire stretching device of the class described comprising a frame, a pair of spring tensioned wire gripping jaws at one end thereof, an operating lever formed of

two pivoted sections fulcrumed to the other end of said frame, coacting jaws carried by said sections and adapted for engagement with the free end of the wire, said jaws being operable when the sections are alined for movement from the frame and releasable when the same are disaligned for return movement, and spring pressed slidale hold-

ing strips slidably mounted on the upper section of said lever and normally positioned adjacent the outer sides of said jaws to hold the wire therebetween. ¹⁰

In testimony whereof, I affix my signature hereto.

ARTHUR JOHNSON.
